COMPRESSOR GOVERNOR

Clyde C. Farmer, Pittsburgh, Pa., assignor to The Westinghouse Air Brake Company, Wilmerding, Pa., a Corporation of Pennsylvania

Application August 13, 1928, Serial No. 299,181
Renewed January 25, 1933

21 Claims. (Cl. 137—153)

This invention relates to pressure regulating devices and more particularly to governors for controlling the admission of steam to a fluid compressor or pump.

5 An object of my invention is to provide an improved steam compressor governor which is simple in construction, cheap to manufacture and efficient in operation.

10 Another object of my invention is to provide an improved steam compressor governor in which the parts subject to wear may be readily removed and replaced, thus reducing the maintenance expense to a minimum.

15 At the present time, superheated steam, at high pressure, is extensively employed in locomotives and it has been found that the heat action of the steam interferes with the proper lubrication of the steam compressor governor piston and also has an injurious effect upon the piston spring, and it is another object of 20 my invention to provide the governor with means whereby the temperature of the piston chamber is prevented from rising to such a degree as to injuriously affect the lubrication of the piston or the temper of the spring.

25 Another object of my invention is to provide a steam compressor governor with means for automatically centralizing the regulating springs and for maintaining them centralized.

30 Another object of my invention is to provide a compressor governor having an improved regulating portion.

35 A further object of my invention is to provide an improved spring ring construction in which the member supported by the ring will prevent the accidental separation of the ring from its support.

40 A still further object of the invention is to provide improved means for supporting a compressor governor.

45 Other objects and advantages will appear in the following more detailed description of the invention.

In the accompanying drawing; Fig. 1 is a sectional view taken vertically through a steam compressor governor embodying my invention; Fig. 2 is a bottom view of a portion of the governor; Fig. 3 is a horizontal sectional view taken on the line 3—3 of Fig. 1; and Fig. 4 is 50 an enlarged detail sectional view illustrating the spring ring construction embodied in the regulating portion of the governor.

The steam compressor or pump governor shown in the drawing is of the so-called double 55 top type, but my improvements may also be

applied in connection with a single regulating top type of governor.

The governor may comprise a steam valve body 1, a cylinder section 2, and a cylinder head 3. The cylinder section 2 is provided with a 60 cylindrical boss 4 which fits into an annular recess formed in the body 1 and the section 2 is clamped to the body 1 by means of bolts 5.

The body 1 is provided with a partition wall 6 which separates the steam inlet chamber 7 from the outlet chamber 8 and is provided with 65 a valve seat for a steam valve 9. The steam valve 9 is carried by a stem 10 which extends upwardly through a bore in a guide bushing 11. The bushing 11 is provided with a circular 70 flange 12 which extends into the recess formed to receive the boss 4 and rests upon a gasket 13, the flange 12 being clamped in place by the bolts 5 when the section 2 is secured to the 75 body 1.

Mounted on a reduced section of the stem 10 is a piston 14, which is secured in place by a nut 15, and said piston works in a slip bushing 16 having an annular flange 17. The flange 17 extends into an annular recess formed at 80 the upper face of the section 2 and is clamped in place when the head 3 is secured to the section 2 by means of bolts (not shown), a gasket 18 being interposed between the clamping faces 85 of the section 2 and the head 3.

The flange 17 of the bushing 16 for a portion of its thickness fits snugly in the recess formed in the cylinder section 2 and for the remainder of its thickness is spaced away from the inner surface of the cylinder portion. By the 90 use of this construction, the bushing will be centered in the casing and further this construction facilitates the removal of the bushing since only a slight upward movement of the bushing is necessary for the upper portion of 95 the flange to clear the top of the cylinder portion 2 when the bushing can be grasped and easily removed. Should the bushing be held fast in the cylinder portion due to corrosion or by a deposit of foreign matter, it will require less force to remove the bushing than if the flange 17 would, for its full thickness, fit the recess snugly. The flange 12 of the bushing 11 is made in the same way to facilitate the removal of the bushing 11 from the steam valve 100 body 1.

The lower end of the bushing 16 is provided with an inwardly extending flange 19.

A cup-shaped barrier plate 21 having an annular flange 22 is mounted with the flange 22 110

engaging a shoulder of the section 2 and a gasket 23 is interposed between the flange 22 and the lower face of the flange 19, so that the flange 22 is clamped in place when the head 3 is secured to the section 2.

5 The flange 19 of the bushing 16 besides serving to clamp the barrier plate 21 in place also serves to strengthen the bushing 16 against distortion.

10 The lower portion of the plate 21 is provided with a central opening into which extends an annular boss 24 of the section 2. A coil spring 25 has one end in engagement with the plate 21 and the other end with the piston 14. The bushing 16 is provided with a plurality of holes 26 which connect the chamber within the bushing with an annular outside chamber 27. The section 2 is provided with openings 28 to permit free circulation of air through the space surrounding the plate 21.

15 The two governor tops each comprise a spring box 29 having screw-threaded engagement in the head 3. A valve seat bushing 30, provided with an annular flange 31, is mounted below the spring box and a flexible diaphragm 33 is mounted to engage the flange. On the opposite side of the diaphragm is a ring 32 which engages the lower end of the spring box 29, so that when the spring box is screwed into place the diaphragm 33 and the seat bushing 30 are clamped in place.

20 Mounted in the valve seat bushing 30 is a valve 34 adapted to engage a seat provided in said bushing and the valve 34 is provided with a rectangular guide head 35, the rounded corners of which engage cylindrical guide walls in the bushing, and when these corners are in such engagement, there will be spaces between the straight sides of the head and the cylindrical guide walls of the bushing, through which fluid under pressure supplied through passages 60 in the bushing is supplied to the chamber at one side of the flexible diaphragm 33.

25 Mounted in a chamber provided in the bushing 30 is a coil spring 36 having one end in engagement with a spring plate 37. The central portion of the spring plate is provided with a rounded depression adapted to receive the rounded end of a stem 38 carried by the valve 34.

30 The lower end of the spring 36 is engaged by a spring plate 39 which is held in place by a spring ring 40 mounted in an annular groove formed in the bushing 30. This spring plate is provided with a shoulder 54 which is preferably continuous around the plate and the under surface of this shoulder rests on the spring ring 40, thus the plate is held in place in the bushing 30. Below the shoulder 54, the plate extends through the ring 40, there being sufficient clearance between this portion of the plate and the ring to permit the plate to assume its proper position in assembling without binding against the ring. This clearance, however, is such that the spring ring cannot accidentally move out of its groove in the bushing. In assembling the device, the spring plate 39 is moved upwardly in the bushing 30, against the pressure of the spring 36, until the lower surface of the plate is above the spring ring groove, as shown in dot and dash lines in Fig. 4 of the drawing, and while the plate is held in this position, the spring ring 40 is snapped into place in the groove, after which the plate is released and the pressure of the spring 36 causes the plate to seat on the spring ring. With the plate thus seated, the

ring 40 will be effectively locked against accidental movement out of its groove.

35 Mounted in the spring box 29 is an adjustable coil spring 41, one end of which bears on a follower plate 42 engaging the flexible diaphragm 33. The upper end of the spring engages a spring plate 43 having a concave upper face 44 which is struck on a large radius and is preferably in the form of a portion of a sphere. Engaging the face 44 is the end of an adjusting screw 45, the engaging face of the screw being struck on the same radius as that of the face 44. The screw 45 has screw-threaded engagement in the upper end wall of the spring box 29 and is provided at its upper end, outside of the spring box, with a head 46. A nut 47 is mounted on the screw, to provide for clamping the screw in its adjusted position. If in assembling the governor, the spring 41 is not mounted centrally of the spring box, the surface 44 and the inner surface of the bolt 45 will, when the screw is turned down, cooperate to automatically centralize the spring and will at all times tend to maintain it in its proper position.

40 In order to relieve the steam pipes 48 and 49 100 of strain due to supporting the governor, a separate supporting member 50 is provided and the under face of the steam valve body 1 is provided with a centrally disposed pad 51 and bosses 52, the faces of which are in the same plane and 105 are adapted to bear on the member 50. The bosses 52 are provided with threaded openings to receive bolts 53, by which the governor is clamped to the member 50. The heads of the bolts 5 are mounted in recesses, such that the 110 outer faces of the bolt heads will be above the plane of the engaging faces of the bosses 52 and the pad 51.

45 The bushing 11 is provided with a chamber 55 which opens into a chamber 56 in the cylinder section 2 and this latter chamber is open to the atmosphere through a passage 57. Possible leakage of steam from the chamber 8, around the stem 10, to the chamber 55 will be free to flow to the atmosphere by way of chamber 56 and 115 atmospheric passage 57. By this construction the chamber 58, defined by the barrier plate 21, bushing 16 and piston 14, will be substantially free from leaking steam. If steam should leak into the chamber 58, it will be free to flow to 120 the atmosphere by way of the holes 26 in the bushing, chamber 27 defined by the bushing 16 and the cylinder portion 2, and atmospheric passage and pipe 59.

50 By employing the barrier plate 21, the spring 25 is prevented from contacting with the metal of the cylinder section 2 and the currents of air which pass through the openings 28 in the cylinder section and through the space defined by the plate and the cylinder section, prevent any 135 considerable heat from being transmitted to the spring 25. Since the chamber 58 is substantially free from leaking steam and is vented to the atmosphere, the temperature of this chamber will not rise sufficiently to interfere with the 140 lubrication of the piston 14.

55 The left hand governor top 29 is known as the "low pressure" top and the right hand governor top as the "high pressure" top. The spring 41 of the low pressure top is responsive to a lower pressure acting on its diaphragm 33 than the spring 41 of the high pressure top.

60 In operation, the chamber at the underside of the diaphragm 33 of the low pressure top is supplied with fluid at the pressure compressed by 150

the compressor into the usual main reservoir (not shown) under certain conditions, while under other conditions the chamber at the underside of the diaphragm 33 of the high pressure top is supplied with fluid under pressure from the main reservoir.

Assuming main reservoir pressure as being supplied to the diaphragm chamber of the low pressure top, when by operation of the compressor, the main reservoir pressure has been increased to a predetermined degree for which the spring 41 of the low pressure governor top may be adjusted, the left hand diaphragm 33 is deflected upwardly, permitting the associated valve 15 34 to be unseated by the pressure of spring 36.

With the left hand valve 34 thus unseated, fluid under pressure is supplied from the diaphragm chamber to the piston chamber at the upper side of the piston 14, causing the piston to 20 operate downwardly seating the steam valve 9 on its seat and thus closing off the further supply of steam to the compressor which causes the compressor to cease operating.

When the pressure of fluid in the main reservoir and in the left hand diaphragm chamber has been reduced below a predetermined degree, the spring 41 of the low pressure governor top operates to deflect the left hand diaphragm 33 downwardly, so that the valve 34 is moved to 30 its seat. The supply of fluid under pressure to the piston chamber being thus cut off, the fluid pressure in said chamber leaks off to the atmosphere, through a restricted port in a plug having screw-threaded connection with the cylinder head portion 3.

The spring 25 then acts on the piston 14 to shift same upwardly, so that the steam valve 9 is again unseated, permitting the supply of steam to the compressor. The compressor then starts 40 operation to compress fluid into the main reservoir.

When fluid from the main reservoir is supplied to the diaphragm chamber in the high pressure governor top 29 at the right, the high pressure governor top then controls the operation of the compressor governor in the same manner as the low pressure governor top functions.

While one illustrative embodiment of the invention has been described in detail, it is not my intention to limit its scope to that embodiment or otherwise than by the terms of the appended 50 claims.

Having now described my invention, what I claim as new and desire to secure by Letters 55 Patent, is:—

1. In a steam pump governor, the combination with a cylinder casing, of a bushing mounted in said casing, a piston mounted in said bushing, a flange on said bushing resting on said casing, a barrier plate resting on said casing, and a flange on said bushing for clamping said plate to said 60 casing.

2. In a steam pump governor, the combination with a cylinder casing, of a bushing mounted in said casing, a piston mounted in said bushing, an upper outwardly extending flange on said bushing resting on said casing, a barrier plate, and a lower inwardly extending flange on said bushing adapted to clamp said barrier plate to 70 said casing.

3. The combination with a governor for regulating the supply of steam to a fluid compressor, said governor having a casing, of spaced bosses carried by said casing, a pad carried by said casing and located between said bosses, a member

for supporting said governor adapted to engage said bosses and pad, and bolts having screw-threaded engagement in said bosses for clamping said member to said casing.

4. The combination with a governor for regulating the supply of steam to a fluid compressor said governor having a casing, of spaced bosses extending outwardly from said casing, a pad extending outwardly from said casing, and a supporting member for said governor engaging said bosses and pad and secured to said bosses only.

5. In a steam compressor governor, the combination with a steam valve body having a valve chamber, a steam valve in said chamber, a cylinder section secured to said body and having a piston chamber, a piston in the chamber in said cylinder section connected to said valve, and a cylinder head secured to said cylinder section, of mechanism mounted in said head for controlling the pressure of fluid on said piston, and a spring box adapted to secure said mechanism to said cylinder head, said mechanism comprising a bushing, a regulating valve in said bushing, a spring in said bushing acting on said valve, a removable ring mounted in a groove formed in said bushing, a seat for said spring supported by said ring and adapted to lock said ring in said bushing.

6. In a steam compressor governor, the combination with a steam valve body having a valve chamber, a steam valve in said chamber, a cylinder section secured to said body and having a piston chamber, a piston in the chamber in said cylinder section connected to said valve, and a cylinder head secured to said cylinder section, of mechanism mounted in said head for controlling the pressure of fluid on said piston, and a spring box adapted to secure said mechanism to said cylinder head, said mechanism comprising a bushing, a spring seat in said bushing, a ring removably mounted in a groove formed in said bushing for supporting said spring seat and means for locking said ring to said bushing within said groove when said seat is in engagement with said ring.

7. In a steam compressor governor, the combination with a steam valve body having a valve chamber, a steam valve in said chamber, a cylinder section secured to said body and having a piston chamber, a piston in the chamber in said cylinder section connected to said valve, and a cylinder head secured to said cylinder section, of mechanism mounted in said head for controlling the pressure of fluid in said piston, and a spring box adapted to secure said mechanism to said cylinder head, said mechanism comprising a bushing having an annular groove formed therein, a ring removably mounted in said bushing within said groove, and a spring seat supported on said ring and having a portion extending through said ring adapted to lock said ring to said bushing.

8. In a steam compressor governor, the combination with a valve for controlling the supply of steam to the compressor, a piston for operating said valve, and means for controlling the operation of said piston, of a spring acting on one side of said piston, a barrier plate interposed between said valve and piston for supporting said spring, and a piston bushing adapted to clamp said plate in place.

9. In a fluid pressure device, the combination with a casing having a recess formed therein, of a slip bushing in said casing, a flange on

- said bushing extending into supporting engagement with said casing and being entirely contained in said recess, the peripheral edge of said flange, for a portion of its thickness only, being 5 adapted to engage said casing within said recess.
10. In a fluid pressure device, the combination with a casing having a recess formed therein, of a slip bushing in said casing, a flange on said bushing extending into supporting engagement 10 with said casing within said recess, the upper portion of the peripheral edge of said flange being adapted to engage said casing within said recess, and the lower portion of the peripheral edge being undercut from the upper portion. 15
11. In a fluid pressure device, the combination with a cylinder casing, of a bushing mounted in said casing, said bushing being substantially Z-shape in longitudinal section, a piston operative 20 in said bushing, and a barrier plate clamped between said casing and bushing for radiating heat from a chamber at one side of said piston to the atmosphere.
12. In a fluid pressure device, the combination with a cylinder casing, of a bushing mounted in 25 said casing, said bushing having an outwardly extending flange in supporting engagement with said cylinder casing and having an inwardly extending flange, a piston operative in said bushing, and a barrier plate clamped between said casing and inwardly extending flange. 30
13. In a fluid pressure device, the combination with a cylinder casing, of a bushing mounted in said casing, said bushing having an outwardly extending flange in supporting engagement with 35 said cylinder casing and having an inwardly extending flange, a piston operative in said bushing, above said inwardly extending flange, and a barrier plate clamped between said casing and inwardly extending flange. 40
14. In a steam pump governor, the combination with a cylinder casing, of a bushing mounted in said casing, a piston mounted in said bushing, and a barrier plate for radiating heat from a chamber at the non-pressure side of 45 said piston to the atmosphere, said plate being clamped between said bushing and casing.
15. In a steam pump governor, the combination with a cylinder casing, of a bushing mounted in 50 said casing, a piston mounted in said bushing, an annular flange on said bushing, and a barrier plate for radiating heat from a chamber at the non-pressure side of said piston to the atmosphere, said plate being clamped between said flange and casing. 55
16. In a steam pump governor, the combination with a cylinder casing, of a bushing mounted in said casing, a piston mounted in said bushing, an inwardly extending flange on said 60
- bushing, and a barrier plate for radiating heat from a chamber at the non-pressure side of said piston to the atmosphere, said plate being clamped between said flange and casing.
17. In a steam pump governor, the combination with a cylinder casing, of a bushing mounted in 65 said casing, a piston mounted in said bushing, and a barrier plate interposed between and engaged by both the bushing and casing and with said bushing defining a non-pressure chamber at one side of said piston, said casing having openings for permitting the free circulation of atmospheric air against the exterior surface of said plate and a port for connecting the non-pressure chamber to the atmosphere. 80
18. In a steam pump governor, the combination with a cylinder casing having ventilating openings formed therein for permitting the free circulation of atmospheric air through the casing, of a piston in said casing, a plate carried 85 by said casing and defining a portion of a non-pressure chamber at one side of said piston, and a spring seated on said plate and engaging the non-pressure side of said piston and constituting a cooling medium for said spring, said plate 90 extending across said openings into the path of circulation of the atmospheric air.
19. In a steam pump governor, the combination with a cylinder casing, of a bushing mounted in 95 said casing, a piston mounted in said bushing, and a plate disposed below said piston and carried by said casing for radiating heat from the non-pressure chamber at one side of the piston, said plate being held in place on the casing by said bushing, the exterior of said 100 plate being freely exposed to the atmosphere for permitting the free circulation of atmospheric air about the plate.
20. In a steam pump governor, the combination with a cylinder casing having ventilating 105 openings formed therein, of a flange on said casing disposed above said openings, a bushing mounted in said casing, a piston mounted in said bushing, and a heat radiating plate clamped 110 between said bushing and flange and extending downwardly across said openings.
21. In a steam pump governor, the combination with a steam valve body, a steam valve mounted in said body, a cylinder section, a piston mounted in said section, a partition wall 115 in said section, and a stem connecting said valve with said piston and extending through a bore in said wall, of a spring acting on said piston and a barrier plate interposed between said wall and said piston for supporting said spring and 120 to prevent transmission of heat from the wall to the spring. 130
